UNITED STATES PATENT OFFICE.

JOHN W. McAULIFFE, OF CHICAGO, ILLINOIS, ASSIGNOR TO THE McAULIFFE MANUFACTURING COMPANY, OF CHICAGO, ILLINOIS, A CORPORATION OF RHODE ISLAND.

WATER-CLOSET.

No. 906,053.

Specification of Letters Patent.

Patented Dec. 8, 1908.

Application filed September 11, 1907. Serial No. 392,386.

To all whom it may concern:

Be it known that I, JOHN W. McAULIFFE, a citizen of the United States, residing at Chicago, county of Cook, State of Illinois, have 5 invented a certain new and useful Improvement in Water-Closets, and declare the following to be a full, clear, and exact description of the same, such as will enable others skilled in the art to which it pertains to make 10 and use the same, reference being had to the accompanying drawings, which form a part of this specification.

My invention relates in general to water-closets and more particularly to the shape 15 and construction of the flushing rim around the bowl.

The object of my invention is to provide a water closet with a seat which will be comfortable for both sexes and will at the same 20 time be so constructed that urine will not be thrown over the front of either the bowl or the seat.

My invention may be generally described 25 as comprising a water closet bowl the top edge of which instead of being in a plane, as is usual, is higher at the top and back than at the sides, and is provided with a protecting flange, extending inwardly from the front thereof. When, as is the case with most 30 forms of water closets, a flushing rim extends around the interior of the upper edge of the bowl, the protecting flange extends inwardly from the front of the rim. When a seat is provided above the bowl, such seat is undu- 35 lated or curved to correspond approximately to the rim. The cover, when employed, is also preferably correspondingly curved.

My invention will be more fully described 40 with reference to the accompanying drawing in which the same is illustrated as embodied in a convenient and practical form and in which,—

Figure 1 is a plan view of the bowl, and Fig. 2 is a central sectional view through the 45 cover, seat and bowl.

The same reference characters are used to designate the same parts in the two figures of the drawing.

A designates a water closet bowl and B an 50 ordinary water connection to supply water to the interior of the bowl.

C indicates the usual discharge conduit.

Reference character A¹ designates a flushing rim surrounding the top of the bowl through a slot in the bottom of which the 55 water is discharged to wash the interior of the bowl. The rim is made curved or undulated so that the sides thereof are lower than the front and back. A protecting flange a¹ projects inwardly from the front of the rim. 60

D indicates a seat curved to correspond to the curvature of the rim, while E designates a cover preferably correspondingly curved. The seat and cover are pivotally connected at their rear edges to the bowl by any suitable means, such for instance as hinges d and e, respectively, connected to the seat and cover and pivoted to a post F.

It will be observed by reference to Fig. 2 that the flange a¹ terminates adjacent to the 70 inner edge of the front of the seat so as to obstruct the usual crack between the rim of the bowl and the seat.

From the foregoing description it will be observed that I have invented an improved 75 water closet bowl which is so shaped and constructed as to be cleanly and comfortable in use.

Having now fully described my invention, what I claim as new and desire to secure by 80 Letters Patent is:

1. In a water closet, a bowl, the upper edge of which is curved so as to be higher at the front and back than at the sides, a seat curved so as to correspond to the curvature 85 of the top of the bowl, and a flange projecting inwardly from the front of the bowl and extending in close proximity to the seat.

2. In a water closet, a bowl the upper edge of which is curved so as to be higher at the 90 front and back than at the sides, a seat curved so as to correspond to the curvature of the top of the bowl, and a flange having a substantially horizontal upper surface extending inwardly a sufficient distance to 95 come into close proximity to the downwardly curving seat.

In testimony whereof, I sign this specification in the presence of two witnesses.

JOHN W. McAULIFFE.
